(57) **CLAIM**

The ornamental design for a ladder tray, as shown and described.

DESCRIPTION

FIG. 1 is a front view of a ladder tray showing my new design;

FIG. 2 is a rear view of the ladder tray;

FIG. 3 is a right side view of the ladder tray;

FIG. 4 is a left side view of the ladder tray;

FIG. 5 is a top view of the ladder tray;

FIG. 6 is a bottom view of the ladder tray; and,

FIG. 7 is a top rear side perspective view of the ladder tray. The broken lines are illustrative of portions of the article forming no part of the claimed design.
